Primary Examiner — Ralf Seifert(74) *Attorney, Agent, or Firm* — The Webb Law Firm(57) **CLAIM**

The ornamental design for a reciprocating pump, as shown and described.

DESCRIPTION

FIG. 1 is a perspective view of a reciprocating pump showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a perspective view thereof in a configuration of use.

The broken lines are included for the purpose of illustrating portions of the reciprocating pump that form no part of the claimed design.
